[57] **CLAIM**

The ornamental design for ski cap with stereo headphone flaps, as shown and described.

DESCRIPTION

FIG. 1 is a rear perspective view of a ski cap with stereo headphone flaps showing my new design;

FIG. 2 is a left front perspective view thereof;

FIG. 3 is front perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a rear elevational view thereof;

FIG. 9 is a bottom plan view;

FIG. 10 is a fragmentary front perspective view thereof;

FIG. 11 is a front perspective view of a second embodiment of a ski cap with stereo headphone flaps showing my new design;

FIG. 12 is a front elevational view thereof;

FIG. 13 is a rear elevational view thereof;

FIG. 14 is a right side elevational view thereof;

FIG. 15 is a left side elevational view thereof;

FIG. 16 is a rear elevational view thereof;

FIG. 17 is a bottom plan view thereof;

FIG. 18 is a left front perspective view of a third embodiment of a ski cap with stereo headphone flaps showing my new design;

FIG. 19 is a front elevational view thereof;

FIG. 20 is a rear elevational view thereof;

FIG. 21 is a right side elevational view thereof;

FIG. 22 is a left side elevational view thereof;

FIG. 23 is a rear elevational view thereof; and,

FIG. 24 is a bottom plan view thereof.

The broken line showing of the human form in FIG. 2 is for illustrative purposes only and forms no part of the claimed design.
